UNITED STATES PATENT OFFICE.

PER NORDENFELT, OF WESTMINSTER, ENGLAND, ASSIGNOR TO THE MAXIM-NORDENFELT GUNS AND AMMUNITION COMPANY, LIMITED, OF SAME PLACE.

APPARATUS FOR CONTROLLING THE RECOIL AND RUNNING OUT OF GUNS.

SPECIFICATION forming part of Letters Patent No. 436,375, dated September 16, 1890.

Application filed May 21, 1890. Serial No. 352,634. (No model.)

To all whom it may concern:

Be it known that I, PER NORDENFELT, engineer, a subject of the King of Sweden, residing at 32 Victoria Street, in the city of 5 Westminster, England, have invented certain new and useful Improvements in Apparatus for Controlling the Recoil and Running Out of Guns, of which the following is a specification.

10 In recoil apparatus in which some of the force of the recoil is stored up by the compression of a spring or otherwise, and is at the end of the recoil allowed to at once run out of the gun, the recoil is usually controlled by a 15 hydraulic cylinder the fluid in which has to pass through a small passage or passages in the side of the cylinder from one side of the piston to the other during the recoil, and power is at the same time stored by the compression of a spring. To control the running forward of the gun by the spring at the end of the recoil, I use a second and independent cylinder, which acts only or mainly during 20 the running out, while the recoil-cylinder acts 25 only or mainly during recoil.

Figure 1 is a longitudinal section of recoil and running-out apparatus in which two cylinders are used. Fig. 2 is a side elevation of a gun and mounting to which this apparatus 30 is applied. Fig. 2^x is a cross-section through the cylinder used for controlling the running out of the gun.

In Fig. 1, A B are two cylinders fixed together end to end in a line with one another. 35 C is a piston-rod passing into both cylinders and having upon it a piston A' for the cylinder A, and a piston B', fitting a lining which is within the cylinder B. The piston-rod passes out through a stuffing-box at the end 40 of the cylinder A, so that its end may be secured to the gun D, while the cylinders are secured to the cradle or carriage E, within which the gun is free to slide endwise, as shown at Fig. 2. Within the cylinder A the piston-rod C is surrounded by a coiled spring Z, one end of which bears against the end of the cylinder, and the other end bears against a collar C', fixed on the rod. The cylinder is also filled with liquid.

45 Through the piston A' are passages A²,

which are closed by a valve F when the piston-rod is drawn outward from the cylinder, but which are open when the piston is moved in the opposite direction. Similarly the piston B' has passages B² through it, which are 55 closed by a valve G when the piston moves in one direction, but not when it moves in the opposite direction, and the valve G opens when F closes and closes when F opens. When the gun recoils and the piston-rod is 60 drawn outward, the spring Z is compressed, and liquid passes from one end of the cylinder to the other through a slot a', formed lengthwise through a portion of the side of a thin tube A³, with which part of the cylinder 65 is lined. At the same time liquid passes from one end of the cylinder B to the other through the passages formed through the piston B', as the valve G then opens freely. At 70 the end of the recoil and when the piston-rod is forced back in the opposite direction by the spring the valve G closes, and liquid has to pass from one end of the cylinder B to the other through a slot B⁴ in the side of a cylindrical lining B⁵, which is within the cylinder 75 B, and the spring is so restrained from effecting the running out of the gun too quickly. As the valve G closes the valve F opens, and the liquid in the cylinder A has no effect in 80 controlling the running out.

In order to be able to vary the speed at which the gun is run out at any time when it may be desired to do so without having to change any of the parts of the mechanism for others or without having to take the mechanism to pieces, I mount the lining-cylinder B⁵ in such a manner that it can be turned within the cylinder B and be locked in any desired position. It is closed at its end, and has a spindle H extending from the center of 90 the end and passing out through a stuffing-box B⁶ at the end of the cylinder B. The outer end of the spindle H has an arm H' fixed upon it, by which it can be turned, and through the end of the arm is screwed a 95 screw H², which when the spindle has been turned into the position desired can be screwed inward and its end made to enter any one or other of a number of holes B⁷, formed in the end of the cylinder B, and the lining-cylinder 100

B^5 will in this way be locked in the position desired.

Between the cylinders B and B^5 is a cylinder B^8 , in which are a number of longitudinal slots B^9 , of different widths, as shown at Fig. 2^x. This cylinder is prevented from turning within the cylinder B by a screw-pin B^{10} , as shown in Fig. 1. When the inner cylinder B^5 is turned into such a position that the slot B^4 formed in it is not opposite to any of the slots B^9 in the cylinder B^8 , the area of the passage by which liquid can pass from one end of the cylinder B to the other is the slot B^4 . If the cylinder is turned so that the slot B^4 is opposite to any one or other of the slots B^9 , then the area of the passage is increased by the area of this slot, and as the slots B^9 are of different widths any desired area of passage from one end of the cylinder B to the other can be obtained.

I claim—

1. The combination, in apparatus for controlling the recoil and subsequent running out of guns, of two separate independent cylinders, each having its own side passages and filled with its own supply of liquid, and one cylinder acting only during recoil and the other only during the running out of the gun, a spring-controlled piston, said cylinders and piston being connected with the gun and the gun-mounting, substantially as described, and means, substantially such as described, for varying from the outside of the apparatus the area of the passage in the cylinder which controls the running out of the gun without varying the resistance offered during recoil.

2. The combination, in an apparatus for controlling the recoil and subsequent running out of a gun, of two separate and independ-

ent cylinders, each filled with its own supply of liquid, one cylinder acting only during recoil and the other only during the running out of the gun, spring-actuated pistons working in said cylinders, said cylinders and pistons being connected with the gun and the gun-mounting, substantially as described, a side passage in the cylinder, which controls the recoil, and an adjustable or variable side passage, substantially such as described, in the cylinder, which controls the running out of the gun.

3. The combination of the gun, the gun-craddle, the two cylinders A B , fixed end to end and to the cradle, the piston-rod C , with a piston upon it for each cylinder and fixed to the gun, the spring Z within the cylinder A and bearing against a collar on the piston-rod, the passage for liquid along the inside of the cylinder A , the passage for liquid along the inside of the cylinder B , the valve in the piston of the cylinder A to allow liquid to pass freely during the running out, the valve in the piston of the cylinder B to allow liquid to pass freely during recoil, and the inner cylindrical lining B^5 of the cylinder B , having a slot in it, and which can be turned so as to bring the slot opposite to any one or other of a number of slots of differing area formed along the interior of the cylinder B or along a lining B^8 , fixed within it, so that the area of the passage by which liquid can pass from one end to the other of the cylinder B can at any time be adjusted.

PER NORDENFELT.
